UNITED STATES PATENT OFFICE.

JOHN WILLIAM WADSWORTH, OF STOKE-UPON-TRENT, ENGLAND, ASSIGNOR TO
MEAKIN & RIDGWAY, OF NEW YORK, N. Y., A FIRM.

DESIGN FOR A PLATE OR SIMILAR ARTICLE.

41,051.

Specification for Design.

Patented Dec. 20, 1910.

Application filed September 27, 1910. Serial No. 584,133. Term of patent 7 years.

To all whom it may concern:

Be it known that I, JOHN W. WADSWORTH, a subject of the King of England, residing at Stoke-upon-Trent, England, have invented a new, original, and ornamental Design for a Plate or Similar Article, of which the following is a specification, reference being had to the accompanying drawing, forming a part thereof.

The figure is a plan view of a plate showing my new design.

I claim—

The ornamental design for a plate or similar article as shown.

JOHN WILLIAM WADSWORTH.

Witnesses:

HUGO MOCK,

HARRY O. ADAMS.
